UNITED STATES PATENT OFFICE.

GUSTAV DÄHNE, OF NEW YORK, N. Y.

ROLLER SMOOTHING-IRON.

1,190,521.

Specification of Letters Patent. Patented July 11, 1916.

Application filed December 16, 1915. Serial No. 67,180.

To all whom it may concern:

Be it known that I, GUSTAV DÄHNE, a subject of the Emperor of Germany, and a resident of New York, in the county of New York and State of New York have invented certain new and useful Improvements in Rolling Smoothing-Irons, of which the following is a specification.

This invention relates to improvements in means for smoothing and polishing textile fabrics in the manner of the ordinary flat iron, and has for its principal object the provision of means whereby such smoothing operations are performed without danger of damaging the fabric by reason of engaging with its fibers, which may be used without previous experience, and with a minimum of effort.

Another object is to combine with the apparatus self-contained means whereby a certain degree of heat may be constantly maintained, subject to the control of the operator, and finally, to provide such implement in forms inexpensive to construct and of general utility.

These and other like objects are attained by the novel construction and combination of parts hereinafter described and shown in the accompanying drawings, forming a material part of this specification, and in which:—

Figure 1 is a front elevation of the apparatus, parts being shown in section, in order to disclose the interior. Fig. 2 is an end view of the same. Fig. 3 is an elevational view, showing a modified form of smoothing iron. Fig. 4 is a partial front elevation and vertical section of the same, and Fig. 5 shows a smoothing iron in its simplest form.

The construction is comprised of a relatively heavy hollow metal roller 10, having a highly polished, finished surface and provided with extending hubs 11, bored to receive and rotate freely upon the hollow cylindrical stems 12 formed with screw threads 15, and hexagonal heads 20 by which they are secured in the frame 16, the upper part of which is bent at right angles bifurcated and formed with arms 17, having between them an operating handle 18.

Passing centrally through the stems is a tube 22, bent upward at 23, beyond the heads and connected with a valve 24, the operating stem 25 of which is arranged conveniently accessible. A continuance of the bent por-

tion 23 rises from the valve 24, as at 26, and communicates with the ends of the reservoir 28, held to the frame 16, by means of the clips 29 and provided with an inlet 30 having a cap or cover 31. This reservoir is adapted to contain any preferred fluid hydro-carbon, or alcohol, which being fed by gravity through the tube and control valve 24, passes through perforations 32 formed in the tube 22 in the hollow roller 10.

In order to admit the entrance of a match or other igniting means, to provide oxygen for the proper maintenance of a flame, and also allow the products of combustion to pass outward, a plurality of openings 33 are provided in the ends of the cylindrical roller 10.

In place of burning the liquid fuel direct, it is preferable to use the same in a gaseous condition which is provided for by means of the concave, saucer shaped starting cup 35 rigidly affixed on the tubes 26 slightly below the reservoir 28 and adapted to contain a small quantity of the fluid used; this being ignited produces heat, directed against the reservoir 28.

In operation the reservoir being filled and heated by the means previously described, the roller may be raised to the desired temperature, after igniting the gas in its interior, and for many purposes will be found superior, as the highly finished, glossy surface of the cylinder is kept uniformly heated and cannot by any chance tend to tear or pick up any loose fibers extending from the fabric upon which it is operated.

In Fig. 3 is shown a preferred form of the smoothing iron, the same consisting of a cylindrical roller 40, having relatively heavy walls as being better adapted to remain in a heated condition, and webbed ends 41 having hubs 42 receptive of the screw threads 43 of the trunnions, the same being formed with a head 44 adapted to receive a wrench and an annular stepped portion 45 receptive of the frame rings 46.

The entire frame 47, twisted portion 48 and handle 49 are preferably formed of a stiff wire, bent as indicated and coiled at the handle portion offering a convenient grip by which the implement is manipulated. A reservoir 50 is attached to the handle elements 47 by means of suitable clips 51 and provided with an inlet 52, by which the contents may be replenished. One end of the reservoir 50 extends outwardly beyond the

frame and has connected a tube 54 on which is positioned a concave open topped receptacle 55 adapted to operate in all respects like the element 35 previously described.

5 The continuation of the tube 54 has upon it a control valve 56, thereafter being bent and passing through an opening 58 in the trunnion, the inwardly extending end 59 being provided with a plurality of perforations 60 through which the gas issues and which may be ignited by the insertion of a match or the like through the openings formed in the web 41. In this form of reservoir it will be readily seen that heat 10 rising from the vessel 55 is received in the center of the reservoir which in this case is made substantially crescent shaped, the lower wall 62 partially encircling the surface of the roller 40 which is separated but 15 a small distance from it. This arrangement is preferable for the reason that heat rising from the roller is transmitted to a considerable extent to the reservoir, causing its contents to gasify without the expenditure of 20 extra material in the cup 55 after it has once been started.

The plain form of roller smoothing iron shown in Fig. 5 consists of the roller 65, and handles 66 revolvably engaged at the ends of 30 the roller which may be removed therefrom while the iron is being heated if preferred.

Having thus described my invention what I claim as new and desire to secure by Letters Patent, is:—

35 1. In a smoothing iron, the combination with a hollow metallic roller, a supporting frame revolvably engaging the ends of said roller, and a handle mounted in said frame

transversely of said roller, of a reservoir adapted to contain liquid fuel attached to 40 said frame, means for filling said reservoir, a tube communicating with the ends of said reservoir, and extending through said roller, said tube having perforated walls within the roller, and means for controlling the passage 45 through said tube.

2. In a smoothing iron, the combination with a hollow metallic roller, having openings through its end walls, a supporting frame revolvably engaging the ends of said roller, and an operating handle in said frame transversely of said roller, of a reservoir 50 adapted to contain liquid fuel, a tube communicating with the ends of said reservoir and extending through said roller, said tube having a perforated wall within the roller, means for initially gasifying the 55 contents of said reservoir and valves controlling passage through said tube.

3. In a smoothing iron, the combination with a heavy walled metallic roller, a supporting frame in which said roller is revolvably mounted and a handle therefor, of a reservoir arranged closely contiguous to said roller, means for initially gasifying the 60 contents of said reservoir, a perforate tube within said roller, connections between said tube and said reservoir and means for controlling the flow therethrough.

Signed at New York, in the county of 70 New York, and State of New York, this 1st day of December, A. D. 1915.

GUSTAV DÄHNE.
